US00D972127S

(12) **United States Design Patent** (10) Patent No.: **US D972,127 S**
 Troll et al. (45) Date of Patent: ** Dec. 6, 2022

(54) **DRUG DELIVERY DEVICE WITH DOCKING STATION**(71) Applicant: **Sensile Medical AG**, Olten (CH)(72) Inventors: **Ilona Julianna Troll**, Baden (CH);
Marco Drüssel, Fulenbach (CH);
Marika Buratti, Aarau (CH);
Christian Schmid, Aarau (CH); **Peter Christen**, Obergerlafingen (CH)(***) Term: **15 Years**(21) Appl. No.: **35/510,998**(22) Filed: **Jun. 22, 2020**(80) **Hague Agreement Data**Int. Filing Date: **Jun. 22, 2020**Int. Reg. No.: **DM/209280**Int. Reg. Date: **Jun. 22, 2020**Int. Reg. Pub. Date: **Dec. 25, 2020**(30) **Foreign Application Priority Data**

Dec. 24, 2019 (CH) 145092

(51) **LOC (13) Cl.** ..... **24-02**(52) **U.S. Cl.**USPC ..... **D24/113**(58) **Field of Classification Search**USPC D24/113, 130; D13/162, 184;

Primary Examiner — Darcey E Gottschalk

(57) **CLAIM**

The ornamental design for a drug delivery device with docking station, as shown and described.

DESCRIPTION

1. Drug delivery device with docking station

1.1 : Perspective

1.2 : Front

1.3 : Back

1.4 : Top

1.5 : Bottom

1.6 : Left

1.7 : Right

The broken lines depict portions of the drug delivery device with docking station that form no part of the claimed design.

1 Claim, 7 Drawing Sheets(56)
